UNITED STATES PATENT OFFICE.

WILLIAM MCINTOSH, OF CLINTON, MASSACHUSETTS.

HOISTING AND CONVEYING APPARATUS.

SPECIFICATION forming part of Letters Patent No. 714,224, dated November 25, 1902.

Application filed February 12, 1902, Serial No. 93,720. (No model.)

To all whom it may concern:

Be it known that I, WILLIAM MCINTOSH, a citizen of the United States, residing at Clinton, in the county of Worcester and State of Massachusetts, have invented a new and useful Hoisting and Conveying Apparatus, of which the following is a specification.

This invention relates to that class of hoisting and conveying mechanisms in which a traveling carriage is mounted to run on an overhead track or cable.

The especial object of this invention is to provide improved mechanism for picking up and releasing the supports for the hoisting-rope, dumping-rope, or other cables which pass to the carriage from stationary windlasses or other sources of power.

To this end this invention consists of the hoisting and conveying apparatus and of the combinations of parts therein, as hereinafter described, and more particularly pointed out in the claims at the end of this specification.

In the accompanying drawings, Figure 1 is a side view of the carriage of a hoisting and conveying apparatus constructed according to my invention. Fig. 2 is a plan view of the same, partially broken away. Fig. 3 is a detail view of the connections for operating the movable hump or detent, the parts being shown in the position they occupy when the carriage is traveling in one direction. Fig. 4 is a similar view showing the parts in the position they occupy when the carriage is traveling in the opposite direction, and Fig. 5 is a detail view illustrating a modified form of construction.

In the use of that class of hoisting and conveying mechanism to which this invention relates, where the carriage is mounted to run on an overhead support or cable of considerable length, it has been found necessary to provide supporting devices for the hoisting-rope, dumping-rope, operating-rope, and other cables which run to the carriage. These supports are located at suitable intervals on the overhead cable, the supports at one side of the carriage being gathered in onto the carriage as the same moves in one direction and being dropped off in proper position as the carriage moves in the opposite direction. Supports of this character may be used on one or both sides of the carriage, although in

practice it is usually necessary to use these supports only on the side of the carriage which receives the hoisting and dumping ropes. To control the picking up and distributing of these supports, it is now usually customary to employ a button-line having stops or abutments for positioning these supports. The use of the button-line, however, for this purpose has been found to be objectionable, as the same is not sufficiently reliable to prevent the apparatus from becoming frequently deranged, causing a stopping of the operation and the necessity of sending a rigger or repairman out on the cable.

To overcome the defects in the operation of the button-line, it has been proposed to provide connections controlled from the operation of the carriage for automatically picking up and distributing these supports.

In both classes of constructions—that is to say, in constructions in which the supports are controlled from a button-line or from automatic connections in the carriage—the supports are gathered in onto a horn mounted in the carriage, the supports hanging on this horn until they are again distributed or dropped into position, when the carriage moves back to the outer limit of its travel. This horn for receiving the supporting devices has heretofore consisted of a horizontal arm provided near its end with a stationary hump or projection, the supports being required to ride up over this hump or projection when gathered in onto the horn or when moved off the horn to be distributed along the cable.

The especial object of my present invention is to improve the construction of the horn or arm on which the supports are strung by making said horn smooth or unobstructed on its supporting-surface, and in providing the same with a movable hump or detent, which is moved down out of the way while the supports are being picked up or gathered in on the horn and which is lifted up into position to hold the supports in place while the carriage is traveling in the opposite direction. The movable hump or horn-detent may be controlled or operated in any desired manner, although I prefer to provide connections for controlling said detent from the travel of the carriage upon its supporting-cable.

Referring to the accompanying drawings

for a detail description of a hoisting mechanism embodying my invention, 10 designates an overhead track or cable.

Running on the cable 10 are the track-wheels 11 and 12, which support the carriage formed by framework 13. Journaled in the framework 13 are the pulleys 15 and 16, which carry the supporting-rope, and the pulleys 17 and 18, which carry the dumping-rope.

The hoisting-rope, dumping-rope, or other ropes leading to the traveling carriage are supported by supports 19, which supports 19 are hung at the required intervals on the cable 10. In the present instance I have illustrated a single support 19, although it is to be understood that a considerable number of such supports are employed in practice.

The supports 19 are picked up or gathered in on a horn or horizontal arm extending from the carriage when the carriage moves in one direction and are distributed at the desired intervals on the cable 10 either by a button-line or by automatic connections for this purpose.

As illustrated herein, the shaft 20 of the wheel 11 is provided with a sprocket-pinion 21, which by means of a sprocket-chain 22 drives the pin-wheel 23. The pin-wheel 23 may be provided with one or more pins 24 for operating a latch 25 when the carriage is traveling in one direction, the latch 25 being provided with a pivoted section at its lower end, permitting the pins 24 to ratchet past the same when the carriage is traveling in the opposite direction. The latch 25 is connected by a link 26 to the pivoted lever 27, which operates the pusher 28, which pusher 28 engages a cam on the support 19 for lifting the same over the detent of the horn to drop the support 19 into place on the cable 10. The latch 25 is also connected by a lever 29 to operate a lever 30, which lever 30 is connected to a spring-pressed cross-bar 31, which normally presses the supports together and which is retracted when a support is to be dropped off. These connections for dropping off the supports 19, as herein illustrated, are of the same construction as the parts shown and described in my application for patent filed October 8, 1901, Serial No. 77,939, and it is to be understood that in this application for patent I do not claim any particular construction for releasing the supports 19, my present invention residing in a special construction of horn and in the connections for operating the movable hump or detent of such horn.

My improved horn, as herein illustrated, consists, essentially, of a horizontal arm 40, projecting from one end of the carriage and provided with a pivoted hump or detent 41. The horizontal arm which forms the supporting-horn is tapered at its end and has a substantially smooth unobstructed supporting surface or top for the carriers.

I use the term "smooth unobstructed supporting-surface" to distinguish from the old

constructions of horn with which I am familiar, which have always had, so far as I am informed, a stationary hump or detent, over which the carriers must be lifted to be taken on the horn and over which they must be lifted when they are detached therefrom.

The detent 41, as illustrated in Fig. 3, is moved down out of the way while the supports 19 are being gathered in on the horn as the carriage travels in one direction and is moved up into raised position to hold the supports 19 in place when the carriage is traveling in the opposite direction.

I preferably provide connections for controlling the position of the movable hump or detent 41 from the travel of the carriage. The preferred form of these connections is most clearly illustrated in Figs. 3 and 4. As shown in these figures, the shaft 42 of the track-wheel 12 has an arm 43 clamped thereon, so as to be frictionally operated. The arm 43 is connected by a link 44 to toggle-levers 45 and 47, which are connected to the movable hump or detent 41. The motion of the toggle-levers 45 and 47 is limited by stop-pins 48. By means of this construction while the supports 19 are being gathered in or picked up on the horn 40 the movable hump or detent will be moved down out of the way, as illustrated in Fig. 3, while when the carriage is traveling in the opposite direction the movable hump or detent 41 will occupy its raised position, as illustrated in Fig. 4. When the hump or detent 41 is in its raised position, as shown in Fig. 4, it will be noted that the toggle-levers 45 and 47 have been moved slightly past their center of motion, providing a positive lock for preventing any strain or pressure upon the movable hump or detent for pushing the same down out of the way.

In Fig. 5 I have illustrated a modification of the connections for operating the movable hump or detent 41. As shown in this figure, the shaft 42 of the track-wheel 12 is provided with a disk 50, carrying a number of pawls 51. One-half of the pawls 51 are faced in one direction, and the other half of the pawls 51 are faced in the opposite direction. A slide 52 is connected by a link 47 to the movable hump or detent 41, which slide 52 is provided with shoulders 53 and 54 for co-operating with the pawls 51. By means of this construction when the carriage is moving in one direction one set of the pawls 51 will engage with the shoulder 53 to move the slide in one direction to draw the movable hump or detent down into its inoperative position, and when the carriage is moving in the other direction the other set of pawls 51, co-operating with the shoulder 54, will raise the hump or detent 41 up into its operative position. A spring-catch 55 may be arranged to co-operate with the slide 52 to lock the same in the position to which it is moved by the pawls 51.

I am aware that numerous changes may be made in the connections for operating the movable hump or detent of my improved

horn, that the shape of the horn and its de-
tent may be widely varied, and that the de-
tent instead of being controlled by the mo-
tion of the carriage may simply be controlled

5 by gravity or by the action of a spring with-
out departing from the scope of my invention
as expressed in the claims.

My device has two points of advantage
over the old constructions. The first is that
10 the carriers are easily picked up on the horn,
especially at slow speeds. In old construc-
tions when running at slow speeds it was
often found necessary to run way over to one
15 side and push the carriers against a fixed
projection before they would be picked up
by the horn.

The second point of advantage in my im-
proved construction resides in the fact that
the hump on the horn can be much larger
20 and higher than with ordinary constructions,
whereby when the carriage runs on an in-
cline or on a sharply-curved rope the incline
or tip of the carriage will not allow the car-
riers to drop off of the horn except when the
25 mechanism or means for this purpose oper-
ates. I do not wish, therefore, to be limited
to the special construction which I have here-
in shown and described; but

What I do claim, and desire to secure by
30 Letters Patent of the United States, is—

1. In a hoisting and conveying apparatus,
the combination of an overhead track or ca-
ble, a carriage mounted to run thereon, a horn
35 on said carriage having a smooth unobstructed
holding-surface, and a hump or detent ar-
ranged so that said horn and said hump or
detent assume different relative positions,
whereby said horn can engage and pick up
40 a fall-rope carrier without substantial ob-
struction from said hump or detent, and
whereby said hump or detent holds said car-
rier after it is picked up by said horn.

2. In a hoisting and conveying apparatus,
the combination of an overhead track or ca-
45 ble, a carriage mounted to run thereon, a horn
in said carriage having a smooth unobstructed
holding - surface upon which supports are
picked up while the carriage is moving in one
50 direction and from which the supports are
distributed when the carriage is moving in
the opposite direction, a movable hump or de-
tent for holding the supports on said horn,
and means for operating the detent from the
55 motion of the carriage.

3. In a hoisting and conveying apparatus,
the combination of an overhead track or ca-
ble, a carriage mounted to run thereon, a horn
in said carriage having a smooth unobstructed
holding - surface upon which supports are
60 picked up while the carriage is moving in one
direction, automatic mechanism mounted in
the carriage and controlled from the travel
thereof for distributing the supports from
the horn while the carriage is moving in the
65 opposite direction, the horn being provided
with a movable hump or detent which moves

out of the way while the supports are being
picked up and which stands in operative po-
sition while the supports are being distrib-
uted.

4. In a hoisting and conveying apparatus,
the combination of an overhead track or ca-
ble, a carriage supported by wheels running
on said track or cable, a horn in said carriage
having a smooth unobstructed holding-sur-
70 face upon which supports are picked up while
the carriage is moving in one direction and
from which the supports are distributed while
the carriage is moving in the opposite direc-
tion, a movable hump or detent for said horn,
75 and connections from one of the carriage-
wheels for operating said hump or detent.

5. In a hoisting and conveying apparatus,
the combination of an overhead track or ca-
ble, a carriage mounted to run thereon, a horn
80 mounted in said carriage upon which sup-
ports are picked up while the carriage is mov-
ing in one direction and from which the sup-
ports are distributed while the carriage is
moving in the opposite direction, a movable
85 hump or detent for said horn, and operating
connections for the movable hump or detent,
forming a positive lock for preventing the
movable hump or detent from being moved
from its operative position by the pressure of
90 the supports thereon.

6. In a hoisting and conveying apparatus,
the combination of an overhead track or ca-
ble, a carriage mounted to run thereon, a horn
100 mounted in said carriage upon which sup-
ports are picked up while the carriage is mov-
ing in one direction, and from which the sup-
ports are distributed while the carriage is
moving in the opposite direction, a movable
105 hump or detent for the horn, and toggle-le-
vers connected to operate the movable hump
or detent from the motion of the carriage,
said toggle - levers being arranged to move
slightly past their center of movement when
110 the hump or detent occupies its operative po-
sition, so as to form a positive lock for hold-
ing the hump or detent in place.

7. In a hoisting and conveying apparatus,
the combination of an overhead track or ca-
ble, a carriage supported by wheels running
115 on the overhead track or cable, a horn mount-
ed in said carriage upon which supports are
picked up while the carriage is moving in one
direction and from which the supports are
distributed when the carriage is moving in
120 the opposite direction, a movable hump or
detent, and an operating-arm having a fric-
tional connection with the shaft of one of the
carriage-wheels for operating the toggle-le-
vers, substantially as described.

In testimony whereof I have hereunto set
my hand in the presence of two subscribing
witnesses.

WILLIAM MCINTOSH.
